BY John A. Baumhardt

ATTORNEY

UNITED STATES PATENT OFFICE.

HENRY BAUM, OF CLEVELAND, OHIO.

COMPOUND TOOL.

Application filed November 30, 1925. Serial No. 72,305.

This invention relates to new and useful improvements in compound tools and more especially to pocket cutting tools.

One object is to provide an improved 5 holder for cutting blades such as ordinary safety razor blades.

Another object is to provide a detachable protective sheath to cover the blade.

A further object is to provide means for 10 adjusting the blade relative to the handle for various usages.

In the drawings:

Figure 1 is a view of the blade holder showing the blade sheath attached;

15 Figure 2 is an edge view thereof;

Figure 3 is a view showing the blade holder unsheathed;

Figure 4 is an edge view thereof;

20 Figure 5 is an enlarged sectional detail on line 5—5 of Figure 1;

Figure 6 is a detail view of the blade holder;

Figures 7 and 8 are views of ordinary safety blades applicable to the holder;

25 Figure 9 is a view of the blade sheath; and

Figure 10 is an edge view thereof.

Referring to the drawings 1 is an ordinary safety razor blade with back binding, 30 adapted to be used as a cutting or scraping blade, removably mounted in a blade holder indicated at 2, formed of stiff spring sheet metal having a folded back portion 3, intermediate offset portions 4 oppositely disposed and opposed spring clamping ends 5 adapted to firmly grip the blade 1 therebetween. The blade back binding 1^a is supported between offset portions 4, abutting against the inner shoulders thereof. The 35 blade is mounted in the holder by inserting the blade endwise between the open spring ends 3 and sliding fully back against stop 6 formed at the opposite end of the holder. Figure 8 shows another form of blade 25 which may be applied.

Blade holder 2 is adjustably mounted between the clevis ends 8 of a handle 7 by means of a pivot pin 9 and snap locking means 10 which comprises a ball 11 set in a 40 retaining hole 12 in a clevis end 8. A leaf

spring 13, pinned at one end as at 14 to handle 7, is cupped at its free end 15 to engage and yieldingly press ball 11 into snap locking engagement with socket 16 formed in the folded portions 3 of holder 2, maintaining the blade at right angles relative to the handle as shown in full lines in Figure 3. With the blade in this position the tool is adapted to be used as a pushable cutting tool, such as a scraper for removing 45 paint from glass, etc. Re-enforcement of the handle mounting, preventing accidental disengagement of the snap locking means, is provided by abutment of the substantially squared clevis tips 8 against offset portions 50 4 of blade holder 2.

When desirable to use the tool as a knife or a drawing cutting tool, or a seam ripper, the blade may be adjusted parallel with the handle as shown in dot and dash lines 55 in Figure 3. This is accomplished by disengaging ball 11 from socket 16 and turning blade holder 2 for 90° about the pivot pin 11, thereby moving socket 18 formed in the folded portion 3 into snap locking engagement with ball 11. In this position the handle mounting is re-enforced and accidental disengagement of the snap locking means prevented by offset portions 4 of holder 2 abutting against the sides of handle 60 clevis ends 8 and the bottom edge of folded portion 3 abutting against stop 19 formed between clevis ends 8.

A protective blade sheath indicated at 20 is provided to protect the blade cutting edge 65 and permit the tool to be safely carried about. Said sheath comprises folded spring sides 21 conforming to slidingly fit over blade holder 2, the slightly inturned edges 22 gripping under offset portions 4. The 70 sheath is applied sidewise, the blade abutting against stop 23 thereof. Inwardly offset tabs 24 also grip under offset portion 4.

The tool presents an attractive appearance, 75 is durable yet of simple and inexpensive construction and possesses a wide range of usefulness.

I claim:

80 A tool comprising a forked handle, a blade 100

2
1,017,500
holder pivoted between the forks of the handle, a blade removably held in the holder, and a spring catch engageable with the holder in various positions of the latter, to present the blade at different angles to the handle, the holder having sockets, and the spring catch comprising a ball carried in a hole in one of the forks of the handle and yieldably engageable in any one of the sockets, and a flat spring secured to the handle and pressing against the outer side of the ball. 10
5
In testimony whereof, I affix my signature.
HENRY BAUM.
